UNITED STATES PATENT OFFICE.

GEORGE A. BERRY, OF EXCELSIOR SPRINGS, MISSOURI.

PRICE-TICKET HOLDER.

1,366,113.

Specification of Letters Patent. Patented Jan. 18, 1921.

Application filed January 7, 1920. Serial No. 349,905.

To all whom it may concern:

Be it known that I, GEORGE A. BERRY, citizen of the United States, residing at Excelsior Springs, in the county of Clay and 5 State of Missouri, have invented certain new and useful Improvements in Price-Ticket Holders, of which the following is a specification.

This invention relates to an improved 10 price ticket holder and has as one of its principal objects to provide a device of this character which may be readily attached to a shelf for supporting a price ticket thereon.

The invention has as a further object to 15 provide a device having jaws for gripping the shelf so that the device will thus firmly engage the shelf.

A still further object of the invention is 20 to provide a device having means for resiliently gripping the price ticket engaged therewith so that accidental displacement of the ticket from the holder will be prevented.

And the invention has as a still further 25 object to provide a price ticket holder which will be particularly simple in construction and which may be formed from a single length of material.

Other and incidental objects will appear hereinafter.

30 In the drawings:

Figure 1 is a perspective view showing my improved price ticket holder in position upon a shelf of conventional type,

Fig. 2 is a plan view of the device,

35 Fig. 3 is a transverse section taken on the line 3—3 of Fig. 2, and looking in the directions of the arrows,

Fig. 4 is a perspective view showing the device in detail, and

40 Fig. 5 is a perspective view showing a slightly modified form of holder.

Referring now more particularly to the drawings, it will be seen that I employ, in carrying the invention into effect, companion shelf clamps indicated as a whole at A and B respectively. Each of these clamps includes an upper jaw 10 and a lower jaw 11 joined by a vertical connecting portion 12. This connecting portion is bent 45 upon itself to provide an upstanding ticket retaining finger 13 free at its upper end and closely confronting the straight shank of the connecting portion to coact therewith. As will be observed, the lower jaw lies in spaced 50 parallel relation to the upper jaw but is

somewhat longer than the upper jaw, being offset upwardly intermediate of its ends and provided with angularly disposed portions forming a foot 14. Coupling the clamps and supporting the clamps in spaced relation is a connecting rod 15 extending between the rear or outer ends of the jaws 10. 60

The device is preferably formed from a single length of suitable resilient wire, the intermediate portion of which forms the 65 connecting rod 15. At the ends of this rod the end portions of the wire are then bent forwardly at substantially right angles to form the jaws 10 when the end portions of the wire are again bent downwardly at substantially right angles to form the shanks of the connecting portions 12. At the lower ends of these shanks, the end portions of the wire are then bent upwardly and thence again downwardly to form the fingers 13 70 when the end portions of the wire are bent rearwardly at substantially right angles to form the jaws 11. At the outer ends of these jaws, the end portions of the wire are then bent laterally toward each other at 75 substantially right angles and thence again bent forwardly at substantially right angles to form the feet 14. It will accordingly be seen that the complete device may be readily produced. 80

In Fig. 1 of the drawings, I have shown the device in place upon a shelf 16 of conventional type. In applying the device, the jaws 10 and 11 of the shelf clamps are first spread to receive the shelf therebetween. 90 The upper jaws 10 are then engaged over the upper surface of the shelf while the lower jaws 11 are engaged with the lower surface of the shelf. The device may then be moved inwardly upon the shelf until the shanks 95 of the connecting portions 12 of the clamps abut the outer edge of the shelf when the jaws of the clamps will yieldably grip the shelf for securely holding the device thereon. A ticket, as conventionally shown at 17, 100 may then be engaged beneath the fingers 13 of the shelf clamps to be supported by the holder upon the shelf, it being observed that the fingers will coact with the shanks of the connecting portions 12 for yieldably gripping the ticket. The ticket will thus be firmly held against accidental displacement and since the ticket, when thus in place, is disposed immediately in front of the forward edge of the shelf, the ticket may be easily 110

seen. Furthermore, by this arrangement, view of the ticket will not likely be obstructed by articles placed upon the shelf.

In Fig. 5 of the drawings, I have shown 5 a slight modification of the invention. In this modification, companion shelf clamps C and D are employed. These clamps each include upper and lower jaws 18 and 19 joined by a connecting portion 20. Coupling the 10 clamps is a connecting rod 21. All of these parts correspond to similar parts of the preferred construction. The modified structure is, like the preferred form of the invention, preferably formed from a single length 15 of suitable resilient wire. The intermediate portion of this length of wire forms the connecting rod 21 and at the ends of this rod the end portions of the wire are looped rearwardly to form the upper jaws 18. From 20 these jaws the end portions of the wire are then bent downwardly at substantially right angles to form the straight shanks of the connecting portions 20 when the end portions of the wire are again bent rearwardly 25 at substantially right angles to form the lower jaws 19. At the outer ends of these jaws, the end portions of the wire are then bent laterally inward toward each other and thence again bent forwardly at substantially right angles to form the feet 22, these feet corresponding to the feet 14 of the preferred construction. The modified structure 30 may thus be readily produced and it will be noted that the ticket retaining fingers as 35 closed in connection with the preferred construction are eliminated. On the other hand, the shanks of the connecting portions 20 are employed for holding the ticket. The device is shown in position on a conventional shelf 40 23. In applying the device the jaws 18 and

19 of the clamps are separated to embrace the shelf when the device may be shifted inwardly upon the shelf. However, before this is done, a price ticket, as conventionally indicated at 24, is inserted beneath the 45 shanks of the connecting portions 20 so that when the device is moved inwardly upon the shelf, the ticket will be clamped between said shanks and the forward edge of the shelf. The ticket will thus be securely held 50 in place.

Having thus described the invention, what is claimed as new is:

1. A device for the purpose set forth formed from a single strand of resilient wire 55 and comprising an intermediate connecting member, upper shelf-engaging jaws extending laterally from the ends of said connecting member, ticket retaining members depending from the ends of said upper jaws and lower shelf-engaging jaws extending laterally from said ticket retaining members, the said lower jaws having return terminals whereby to obtain an extended engagement with the under side of the shelf. 65

2. A device for the purpose set forth formed from a single strand of resilient wire and comprising an intermediate connecting member, upper shelf-engaging jaws extending laterally from the ends of said connecting member, lower shelf-engaging jaws, and connections between the upper and lower jaws, said connections including a pendant U-shaped portion carried by the upper jaw and a return bend extending downwardly 70 from the upper front end of said U-shaped portion to the lower jaw. 75

In testimony whereof I affix my signature.

GEORGE A. BERRY. [L. S.]
